UNITED STATES PATENT OFFICE.

RICHARD A. BREUL, OF BRIDGEPORT, CONNECTICUT, ASSIGNOR TO THE BRIDGEPORT CHAIN COMPANY.

FEEDING MECHANISM FOR BLANKING-PRESSES.

SPECIFICATION forming part of Letters Patent No. 395,211, dated December 25, 1888.

Application filed May 8, 1888. Serial No. 273,182. (No model.)

To all whom it may concern:

Be it known that I, RICHARD A. BREUL, a citizen of the United States, residing at Bridgeport, in the county of Fairfield and 5 State of Connecticut, have invented certain new and useful Improvements in Feeding Mechanism for Blanking-Presses; and I do hereby declare the following to be a full, clear, and exact description of the invention, such 10 as will enable others skilled in the art to which it appertains to make and use the same.

My invention has for its object to produce a device of this class that will cut blanks longitudinally of a strip of metal which is passed 15 from side to side under the plunger, then fed forward, and passed back again, these movements being repeated continuously, the forward portion of each alternate row of 20 blanks being cut from portions of the strip of metal left between the row of blanks last cut, thus reducing the amount of scrap to the minimum and furnishing blanks with the grain running longitudinally thereof, which 25 is an important advantage when they are to be used in places where tensile strength is required—as, for example, in the manufacture 30 of sheet-metal chain. It will of course be understood, however, that my improved machine is adapted to general blanking purposes without 35 regard to the shape or size of the blanks or the use for which they are intended, the especial objects gained being rapidity of operation, minimum waste of metal, and the securing of the maximum tensile strength in 40 the blanks.

My invention furthermore consists in combining with the feeding mechanism a cutter which chops the scrap up into small pieces, thereby increasing its value for melting up 45 without necessitating a special operation to cut it.

With these ends in view I have devised the novel construction of which the following description, in connection with the accompanying 50 drawings, is a specification.

Figure 1 is a plan view of the entire machine, the plunger and movable cutter being removed; Fig. 2, a front elevation, the rear feed-pawl bracket being omitted; Fig. 3, a 55 rear elevation, the front feed-pawl bracket and the cutting mechanism being omitted; Fig. 4, a side elevation, the view being from the left in Fig. 2; Fig. 5, a section on the line

x x in Fig. 1, looking toward the left; Fig. 6, a detail view of the cam which operates the 55 cross-feed; Fig. 7, a detail view of the rollers. Figs. 8 and 9 are respectively plan and edge views of the cam-lever for adjusting the feed-rollers, and Fig. 10 is a diagram illustrating the manner in which the blanks are cut from 60 a strip of metal.

Similar numbers denote the same parts in all the figures.

1 denotes the bed of the blanking-press; 2, the plunger; 3, the holder for the male die 3^a, 65 which may be of the ordinary or any preferred construction, they having nothing whatever to do with the principle of my invention.

The parts of my novel feeding mechanism may be attached to an independent plate or 70 directly to the bed of the press. In the present instance I have shown certain of the parts as carried by a plate, 4, secured to the bed of the press by screws 5.

6 denotes a plate having an opening, 7, 75 through it, which is adapted to slide in ways 8 on plate 4.

9 denotes dogs attached to plate 6 and extending forward toward the front, where they are connected by a cross-piece, 10, the purpose of which will presently be fully explained.

11 and 12 denote, respectively, the upper and lower feed-rollers, both of which are roughened at the center, as shown, and are 85 journaled in blocks 13 between pairs of standards 14, the upper blocks resting on spring 15, which act to lift the upper roller, separating them slightly, so that a strip of metal may be inserted or removed when pressure is removed 90 from the block.

16 is a removable cross-piece between the standards at the top.

17 is an adjusting-lever having upon its upper side curved grooves 18, the ends of said 95 grooves forming inclines, as clearly shown in Fig. 9. This lever is journaled on a pin, 19, projecting downward from the cross-piece, which also carries set-screws 20, adapted to engage the groove in the top of the lever. 100

21 is a spring cross-piece lying between the standards, its opposite ends resting upon the blocks in which the upper feed-roller is journaled. It will be clearly seen that when adjusting-lever 17 is turned so that the points 105 of the set-screws engage grooves 18 springs

15, upon which the upper blocks rest, will act to raise said blocks, lifting the upper roller away from the lower roller, as in Fig. 7, and that when the lever is turned so that the 5 points of the set-screws ride up the inclines upon the full thickness of the lever the spring cross-piece and blocks in which the upper roller is journaled will be forced down, placing the upper roller in operative position 10, as shown in Figs. 4 and 5. The pressure of the upper roller upon the strip of metal may be adjusted by turning the set-screws in or out. The spring of cross-piece 21 in use is amply sufficient to compensate 15 for any irregularities in the thickness of the strip of metal that is being fed to the machine, so that stoppage cannot occur from that cause. The standards are made integral with a plate, 22, which slides in ways in a 20 plate, 23, secured to the bed of the press, plate 22 being held in operative position by plates 24. (See Figs. 1 and 2.)

25 denotes notches in the dog 9 at the right of the machine, (see Fig. 1,) which are engaged by standards 14, so that plate 22 and the entire feeding mechanism are caused to move with plate 6, the strips, and cross-piece 10.

26 is a block having a longitudinal groove, 30 27, to receive the female die 28, said die being held at the desired adjustment by a key, 29.

30 is a stripper secured to the block, under which the strip of metal passes in the operation of blanking, there being just space between the die and stripper for the metal to 35 pass freely.

It will of course be understood, although not shown in the drawings, that the block is open under the die in the usual manner, so 40 that the blanks when cut drop out below. Stripper 30 is provided with an opening, 31, through which the male die passes as it descends, the stripper acting to prevent the strip from being lifted by engagement with 45 the male die.

32 is a guide-roller on the left dog 9, and 33 guide-rollers carried by a slide, 34, which is secured to cross-piece 10 and slides in a cross-groove, 35, in block 26 as the parts move 50 backward and forward in the operation of feeding, all of which will presently be more fully explained.

In order to provide for slight variation in the width of the strips of metal and to enable me to hold said strips firmly, I place one 55 of the rollers 33 on a slide, 36, dovetailed to cross-piece 34. The slide is held in place by a screw, 37, passing through a slot, and is forced forward into operative position by a 60 spring, 38, bearing against the rear end of the slide. The shafts of the feed-rollers are provided with gear-wheels 39, meshing with each other, and the shaft of the lower feed-roller is provided at its opposite ends with ratchets 65 40, which are engaged by hooked pawls 41, pivoted to brackets 42, depending from the plunger. In the present instance the brackets

are shown as connected to arms 43, said arms being rigidly secured to the plunger.

44 denotes springs secured to the brackets 70 and bearing against the backs of the pawls to hold them in operative position, as clearly shown in Figs. 2, 3, and 4.

45 (see Figs. 1 and 2) is a spring-pawl secured to one of the standards and bearing 75 against one of the ratchets to prevent its being moved by jarring of the machine, so that said ratchets will always be in position to be engaged by one of the hooked pawls at the completion of either of the cross movements, 80 as will presently be explained.

46 denotes a yoke secured to plate 4, and 47 an oscillating lever pivoted to said bracket. The upper end of this lever is provided with a roller, 48, engaging a cam-groove, 49, in a 85 plate, 50, carried by the plunger. At the lower end of lever 47 is a spherical roller, 51, engaging slot 52 in a plate, 53. This plate is journaled on a stud, 54, projecting upward from plate 4. Below plate 53 is a ratchet, 55, 90 rigidly secured to a disk, 56, having ratchet-teeth 56^a at its edge and provided on its under side with a cam-groove, 57. Below the disk is the reciprocating plate 6, which carries a roller, 58, engaging the cam-groove in 95 the disk.

59 is a boss on plate 4, projecting upward into opening 7, but not engaging said opening, said boss serving as a support for stud 54.

60 is a hooked pawl pivoted to the under 100 side of plate 53, which is adapted to engage ratchet 55 to carry said ratchet and disk 56 forward at each oscillation of plate 6.

61 is a spring engaging pawl 60 and acting to hold the hook in engagement with a tooth 105 of the ratchet.

62 is a spring-actuated pawl which engages the teeth of ratchet 55, acting to hold it against backward movement.

63 is a spring-actuated pawl adapted to engage one of the ratchet-teeth in the edge of 110 said disk at the proper instant to lock said disk against being carried forward too far when actuated by the engagement of hooked pawl 60 with ratchet 55.

64 is an arm projecting forward from plate 53, which engages the inner side of pawl 63 and acts to lift said pawl out of engagement with the disk when ratchet 55 is engaged by pawl 60. The function of this pawl is to lock 120 the disk against being carried forward too far by the engagement of pawl 60 with the ratchet. It will be noticed (see Fig. 1) that as plate 53 and the arm swing toward the left the arm passes out of engagement with pawl 63, allowing said pawl to drop down and engage one of the teeth of the ratchet to lock it against further forward movement. The return movement of the plate and arm lifts the pawl again out of engagement with the disk, so 125 that it may move forward again when the plate and pawl move toward the left, all of these movements being clearly illustrated in Fig. 1. (See, also, Figs. 3 and 5.)

The operation of this portion of the machine is as follows, all of the parts being actuated from the plunger: In inserting a strip of metal adjusting-lever 17 is turned so as to 5 allow springs 15 to lift the upper roller, and the strip of metal is passed forward under the male die. Lever 17 is then turned back again to clamp the upper feed-roller upon the strip. It will of course be apparent that the lower 10 feed-roller may be made adjustable, if preferred. The machine is now ready to start. It is of course preferable to insert the strip of metal when reciprocating plate 6 is at one extreme or the other of its movement. This, 15 however, is not essential. Let us suppose that the strip is inserted when reciprocating plate 6 is at the extreme of its movement toward the back of the machine, as viewed in Fig. 2, this position of the parts being clearly illustrated 20 in Fig. 4. The last downward movement of the plunger has, through the operation of oscillating lever 47, plate 53, the pawl, ratchet, cam-disk, &c., as shown in Fig. 1, moved plate 6 and all of the parts carried 25 thereby, including the feed-rollers and the strip of metal, toward the right of the machine, as seen in Fig. 4—that is, toward the front, as seen in Fig. 2—and the last portion of the upward movement has actuated the 30 feed-rollers and carried the strip of metal forward through the engagement of the left hooked pawl 41, as seen in Fig. 4, with the left ratchet 40. The result of these lateral and forward movements of the strip has been 35 to place the strip in such position relatively to the dies that the next downward movement of the plunger will strike out a blank the forward end of which shall be cut from metal between the rear ends of the last two 40 blanks struck out. It will of course be apparent from Fig. 4 that the downward movement of the plunger which cuts the first blank after the forward and lateral movements of the strip just described will, through the operation 45 of oscillating lever 47 and the parts operating in connection therewith, carry reciprocating plate 6, plate 22, the feeding mechanism, &c., far enough toward the right, as seen in Fig. 4, to place the strip in the proper 50 position to receive the next blow of the male die. It should be noted that this lateral movement of plates 6 and 22, the feeding mechanism, &c., will carry the left ratchet 40 far enough toward the right so that it will 55 not be engaged by the left hooked pawl 41 when the upward movement of the plunger takes place. It will thus be seen that the feed-rollers, while holding the strip of metal firmly at all times, do not act to carry it forward, except when the last blank has been struck out from either edge of the strip, the metal being supplied to the dies by the lateral movement of the strip caused by the reciprocation of plate 6: 60

65 Turning now to Fig. 1, I will describe more clearly the operation of the mechanism which actuates plate 6 and carries the strip of metal

from left to right, and vice versa. As already stated, the position of the parts in Figs. 4 and 1 corresponds, the plunger being at the raised 70 position. It may be added, furthermore, that the parts are in same position in Figs. 2, 3, and 5, the lower end of lever 47 being swung toward the left, as viewed from the front. The downward movement of the plunger through 75 the engagement of roller 48 with cam-groove 49 swings the oscillating lever and plate 53 toward the right. As the plate swings around, hooked pawl 60, carried thereby, is moved around also, carrying ratchet 55 and disk 56 80 with it. This movement of the disk imparts a movement to plate 6 through the engagement of rollers 58, carried thereby, with the cam-groove. These movements continue until the feed-rollers and the strip have been 85 carried to their extreme position toward the right, as seen in Fig. 4—that is, the reverse of the position shown in said figure. This will place the right hooked pawl 41 in engagement with the right ratchet 40, so that 90 after the last blank has been struck out from the strip on the right side the upward movement of the plunger will cause the forward movement of the feed-rollers, and at the same time oscillating lever 47 and the parts acting 95 in connection therewith will impart the usual lateral movement to the strip. This will place the strip in such position relatively to the dies that the next blow of the male die will strike out the first blank from the next series, the 100 forward portion of which, as usual, is cut from metal left between the rear ends of the last two blanks struck out. In order that this may be clearly understood, attention is called to Fig. 10, which is a diagram illustrating the 105 manner in which the blanks are cut from the strip of metal, and to Fig. 6, which is an inverted plan view of disk 56, showing the cam-groove in the under side thereof. The strip shown in the present instance is of sufficient 110 width to produce the wide ends of four blanks of the style shown and also the narrow ends of four other blanks which are cut from between the wide ends of the row last cut. It is of course understood that in this class of 115 work the great desideratum is to produce as many blanks as possible from the strip of metal fed to the machine, so that the quantity of scrap shall be reduced to the minimum. An independent opening is left in the strip 120 of metal where each blank is cut out, as it is necessary that each blank be cut from solid metal.

For convenience I have designated the first four blanks cut from the strip of metal 125 as it moves from left to right in Fig. 4—that is, from the extreme of its movement toward the back, as seen in Fig. 1—toward the front as, respectively, *a*, *b*, *c*, and *d*. The upward movement of the plunger after blank *d* has 130 been cut out causes the first forward movement of the strip referred to, and the next downward movement produces the first of the reverse lateral movements, the two move-

ments acting to place the strip in position for blank *e* to be cut out, which is the first blank of the return series as the strip moves from the reverse of the position shown in Figs. 1 and 4 toward the position shown in said figures. The next three blanks are denoted by *f*, *g*, and *h*, it being understood that the forward portions of blanks *e*, *f*, *g*, and *h* are cut from solid metal left between the rear portions of blanks *a*, *b*, *c*, and *d*. The next upward and downward movements of the plunger after the blank *h* has been cut produce the second forward movement of the strip referred to, accompanied by a lateral movement, which places the strip in position relatively to the dies for another blank, *a*, to be cut, these movements being continuously repeated as long as the strip holds out. The scrap left after cutting out the blanks is ordinarily melted over. It is, however, quite bulky and requires to be cut up into small pieces before going to the melting-pot. In order to avoid the additional operation of cutting up by the user, and also for the convenience of the maker of the scrap in packing it, I provide a scrap-cutter which operates in connection with the plunger and feeding mechanism to cut the scrap up into small pieces.

65 is a bracket depending from one of the arms 43, to which the upper cutter, 66, is attached.

67 denotes the lower cutter, which is secured to an angle-plate, 68, which in turn is rigidly secured to the bed of the press. Upon the top of the angle-plate is a block, 69, to which a holding-bar, 70, is secured. The scrap as it is fed forward by the feeding mechanism, having passed the dies, is acted upon by the cutters at each movement, the strip of scrap passing under the holding-bar, by which it is held against displacement. As the strip moves across the bed in the lateral feeding movements, the cutters of course do not act upon it; but after each forward movement the next downward movement of the upper cutter cuts a length from the end of the strip of scrap equal to the amount of metal that was fed forward.

The cutters are ordinarily so located relatively to the dies as to cut the strip of scrap midway of the openings where the blanks are cut out—as, for instance, at or about the line where the letters *a*, *b*, *c*, and *d* are placed at the right in Fig. 10—so that the scrap is reduced to small pieces.

It will of course be understood that the details of construction may be varied within reasonable limits without departing from the spirit of my invention.

60 I claim—

1. In a machine of the class described, the combination, with the dies, of a laterally-reciprocating plate carrying the feed-rollers whereby the strip is fed transversely to the dies, so that the blanks are cut out in a row across the width of the strip.

2. The combination, with the dies, the plunger, and the feed-rollers, of a laterally-reciprocating plate by which the feed-rollers are carried, mechanism, substantially as described, for actuating the feed-rollers intermittently to feed the strip of metal forward, and upper and lower cutters by which the scrap is cut up.

3. The combination, with the plunger and reciprocating plate 22, carrying standards 14, of the feed-rollers journaled in blocks supported by said standards, gears 39 on the shafts of said rollers, and ratchets 40 on one of said shafts, which are engaged by pawls 80 41, carried by the plunger, to impart forward movements to the feed-rollers at the extremes of the movements of said plate.

4. The combination, with the plunger carrying arms 43 and reciprocating plate 22, carrying standards 14, of the feed-rollers whose shafts are journaled in blocks supported by said standards, gears 39 on said shafts engaging each other, and ratchets 40 at the opposite ends of one of said shafts, which 90 are engaged by hooked pawls carried by brackets depending from arms 43, substantially as described.

5. Plate 22, having standards 14, blocks 13, the feed-rollers whose shafts are journaled 95 in said blocks, springs between said blocks acting to raise the upper roller, and means, substantially as described, for forcing and holding the upper arm in operative position against the power of said springs.

100 6. The standards, feed-rollers, blocks 13, and springs 15, in combination with cross-piece 16, engaging said standards and having set-screws 20, a spring cross-piece resting on the upper blocks, and an adjusting-lever 105 adapted to bear on said plate and having grooves engaged by the set-screws, whereby the turning of said lever will force the upper feed-roller down to operative position or release it, so that it may be raised by the springs. 110

7. The standards, blocks 13, the feed-rollers whose shafts are journaled in said blocks and are provided with gears 39, engaging each other, and springs 15 between the upper and lower blocks, in combination with cross-piece 115 16, engaging the standards and having a pin, 19, and set-screws 20, spring cross-piece 21, bearing on the upper block, and adjusting-lever 17, journaled on said pin and bearing on the spring cross-piece, and having grooves 18, 120 engaged by said set-screws, as and for the purpose set forth.

8. The combination, with plate 22, the standards, and the feed-rollers, of sliding plate 6, having dogs 9 secured thereto, one of 125 said dogs having notches 25, engaged by the standards, so that plate 22 and the feeding mechanism are moved laterally with plate 6.

9. The combination, with plate 6, having roller 58, and the feeding mechanism carried 130 thereby, of disk 56, having cam-groove 57, with which said roller engages, and means, sub-

stantially as described, for imparting intermittent rotation to said disk.

10. The combination, with plate 6, having a roller, 58, disk 56, having a cam-groove engaged by said roller, ratchet 55, secured to said disk, and stud 54, on which said ratchet and disk are journaled, in combination with an oscillating plate, also journaled on said stud, a hooked pawl pivoted to said plate and 10 engaging the ratchet, and pawl 62, acting to hold the ratchet against backward movement.

11. The combination, with the plunger having a plate with a cam-groove, 49, yoke 46, and a lever, 47, pivoted thereto and having a 15 roller engaging said cam-groove, in combination with plate 53, having a slot engaged by the lower end of said lever and carrying a hooked pawl, 60, ratchet 55, engaged by said pawl, disk 56, secured to said ratchet, and 20 pawl 62, whereby the ratchet is held against backward movement.

12. The combination, with oscillating plate 53, having arm 64 and carrying hooked pawl 60, of disk 56, having ratchet-teeth 56^a in its 25 edge, ratchet 55, secured to said disk, and pawl 63, which engages ratchet-teeth 56^a and is engaged by arm 64, whereby oscillation of said plate in one direction lifts said pawl, so that the disk can be carried forward by the oscillation in the opposite direction, arm 64 permitting said pawl to drop and lock said ratchet at the proper time.

13. The combination, with plate 6, having roller 58, disk 56, having a cam-groove engaged by said roller, and ratchet 55, secured to said disk, of oscillating plate 53, carrying a hooked pawl engaging said ratchet, and an oscillating lever engaging said plate, as and for the purpose set forth.

40 14. The combination, with plate 6, having roller 58, disk 56, having ratchet-teeth in its edge and a cam-groove engaged by said roller, and ratchet 55, secured to said disk, of oscillating plate 53, carrying a hooked pawl engaging said ratchet and having an arm, 64, and pawl 63, which engages the ratchet-teeth and is engaged by said arm, as and for the purpose set forth:

15. The combination, with plate 6, having 50 roller 58, disk 56, having a cam-groove engaged by said roller and teeth 56^a, and ratchet 55, secured to said disk, of oscillating plate 53, carrying a hooked pawl engaging said ratchet and an arm, 64, a pawl, 63, which engages ratchet-teeth 56^a and is engaged by said arm, and pawl 62, which engages the ratchet, as and for the purpose set forth.

16. The combination, with disk 56, ratchet 55, secured thereto, and oscillating plate 53, 60 having a hooked pawl engaging said ratchet, of lever 47, engaging said plate and having a roller at its opposite end, the plunger, and a plate carried thereby, which is provided with the cam-groove engaged by said roller.

65 17. The combination, with the plunger and block 26, having groove 35, and the dies, of

sliding plate 6, having dogs 9 and cross-piece 10, slide 34, secured to said cross-piece and moving in said groove, a spring-actuated slide, 36, carried by slide 34, and guide-rollers on 70 said slides by which the strip of metal is held.

18. The combination, with the plunger and dies, of plate 6, having dogs 9, one of said dogs having notches 25, and plate 22, having standards which support the feed-rollers and are 75 engaged by notches 25, as and for the purpose set forth.

19. The combination, with the plunger and dies, of plate 6, having dogs 9, one of said dogs having notches 25, cross-piece 10, plate 22, 80 having standards which support the feed-rollers and are engaged by notches 25, slide 34, connected to the cross-piece, spring-actuated slide 36, dovetailed to slide 34, and guide-rollers on said slides, whereby the strip 85 is held in the forward and lateral feeding movements.

20. The combination, with sliding plate 6 and the feed-rollers carried by plate 22, of the plunger and upper cutter carried thereby and 90 the lower cutter, substantially as and for the purpose set forth.

21. The combination, with the plunger, sliding plate 22, and the feed-rollers carried thereby, of the upper cutter carried by the 95 plunger, the lower cutter, and holding-bar 70, as and for the purpose set forth.

22. The combination, with the plunger and the feed-rollers, the shafts of said rollers being geared together and one of said shafts 100 having ratchets at its ends, of a sliding plate by which the feed-rollers are carried, and spring-pawls carried by the plunger, which engage said ratchet to impart a forward movement to the feed-rollers at the extremes of 105 the lateral movements.

23. The combination, with the plunger having arms 43 and brackets 42, and feed-rollers, the shafts of said rollers being geared together and one of said shafts having ratchets 110 at its ends, of a laterally-sliding plate by which the feed-rollers are carried, and spring-pawls pivoted to brackets 42, which engage said ratchets to impart a forward movement to the feed-rollers at the extremes of the lateral movements.

24. The combination, with the plunger, the feed-rollers, gears on the shafts of said rollers, and ratchets at the ends of one shaft, of a laterally-sliding plate by which the feed-rollers 120 are carried, spring-pawls carried by the plunger, which engage said ratchets to impart a forward movement to the feed-rollers at the extremes of the lateral movements, and a pawl, 45, engaging one of the ratchets to 125 prevent backward movement.

In testimony whereof I affix my signature in presence of two witnesses.
